Atty.

United States Patent Office.

WILLIAM HARLES, OF WASHINGTON, MISSOURI.

Letters Patent No. 90,533, dated May 25, 1869.

IMPROVEMENT IN MACHINES FOR THREADING RODS, BOLTS, &c.

The Schedule referred to in these Letters Patent and making part of the same.

To all whom it may concern:

Be it known that I, WILLIAM HARLES, of Washington, in the county of Franklin, and State of Missouri, have invented a new and valuable Improvement in Blacksmiths' Screw-Cutting Machines; and I do hereby declare that the following is a full, clear, and exact description of the construction and operation of the same, reference being had to the annexed drawings, making a part of this specification, and to the letters and figures of reference marked thereon.

Figure 1 of the drawings is a plan view of my invention.

Figures 2 and 3 are details.

My invention has relation to machines for cutting screws; and

It consists mainly in a novel arrangement of devices, having in view a light and portable apparatus to be operated by hand, by which a screw-thread may be readily and easily cut upon the end of a rod of any practicable size or length.

The letter A of the drawings represents a firm metallic frame, arranged for being attached upon a bench by bolts or screws in the ears b.

The letter C represents a sliding frame, cut out at its centre to hold the dies, and adjusted by its jaws c upon flanches of the frame, in such manner as to be easily moved or slid back and forth.

The letters h represent dies adjusted by the set-screw i, in the sliding frame C, in the manner shown.

The letter D is a crank-wheel, affixed to a shaft, E, that revolves in bearings upon the side of the main frame, as represented on fig. 1; and

The letter G is a cogged wheel, also affixed to said

shaft, that works in conjunction with the cogged wheel H next mentioned.

The letter H represents a cogged wheel attached firmly upon the end of a shaft that rotates in a journal-box arranged upon the end of the main frame, or, as is preferable, I cast the wheel H and the last-mentioned shaft in one piece, and arrange it in the journal-box, as shown.

The letter s represents a square opening that passes through the centre of the wheel H and its shaft in a longitudinal direction. It is gradually tapered from its front to its rear, and is intended for holding the rod, upon which a screw is to be cut, while the cutting-process is being carried on.

In order to operate my device successfully, the operating person must take a rod of iron that is fashioned with one square and one round end. The square end is held firmly in the quadrangular opening s, and the round end is passed through the dies by turning the crank of the wheel G.

What I claim as my invention, and desire to secure by Letters Patent, is—

The improved screw-cutting machine herein described, having frames A and C, wheels D, G, and H, and the quadrangular opening s, constructed, arranged, and operating substantially as herein specified.

In testimony that I claim the above, I have hereunto subscribed my name, in the presence of two witnesses.

WILLIAM HARLES.
